DRIVE MECHANISM FOR CLOTHES WRINGERS

Thomas W. Behan, Binghamton, N. Y.

Application August 30, 1937, Serial No. 161,562

2 Claims. (Cl. 192—82)

This invention relates to clothes wringers and more particularly to an improved type of drive mechanism therefor.

A primary object of this invention is the provision of a driving mechanism for a clothes wringer having means whereby the rollers may be rotated in either direction, including a clutch and simplified mechanism whereby the power for moving the clutch from any of its positions to any other is produced by the driving mechanism itself.

A further object is the provision of means in association with such a clothes wringer whereby the operator may reverse the direction of rotation of the rollers and start or stop the same by the application of an exceedingly light pressure to a control handle.

An additional object is the provision of means associated with the drive mechanism of a clothes wringer whereby the position of the clothes wringer may be varied and the same rotated about an axis in alignment with the driving shaft without the necessity of manually manipulating any lock or set screw or analogous mechanism.

A still further object is the provision of such a structure as described in the preceding paragraph wherein the wringer may be rotated about the axis above mentioned only when the rollers are inoperative and whereby the mechanism is locked against such rotation during those periods when the wringer rollers are rotating in either direction.

Other objects will in part be obvious and in part pointed out hereinafter.

The invention, therefore, consists in the combinations of elements, arrangements of parts, and features of construction, all as will be pointed out more fully hereinafter and disclosed in the accompanying drawings wherein:

Figure 1 is a side sectional view of one form of mechanism embodying the inventive concept.

Figure 2 is a sectional detail view along the line 2—2 of Figure 1 as viewed from the top, certain parts being omitted to more clearly show the elements intended to be disclosed.

Figure 3 is a sectional view along the line 3—3 of Figure 2 as viewed from the bottom.

Figure 4 is a sectional view along the line 4—4 of Figure 2 as viewed from the bottom.

Figure 5 is a sectional view taken along the line 5—5 of Figure 4 as viewed from the bottom.

Similar reference characters denote similar parts throughout the several views of the drawings.

Referring now to the drawings in detail there

is generally indicated at 10 a housing or casing enclosing the drive mechanism forming a portion of the instant invention. Casing 10 is provided with an aperture 11 through which is passed a vertically extending drive shaft 12 journaled at its upper extremity in a recess 13 which may comprise an integral part of the casing 10. Drive shaft 12 has mounted thereon a freely revolvable gear 14 and a second similar but oppositely positioned gear 15. Gears 14 and 15 both engage a third gear 16 which in turn is rigidly secured to a driving member 17 as by a pin 18 which serves to drive one of a pair of conventional wringer rollers (not shown). A clutch member generally indicated at 20 is positioned between gears 14 and 15 non-rotatably secured to drive shaft 12 in a manner to be herein-after described. Thus from the foregoing it will be seen that upon movement of clutch member 20 to engage gear 15 in a manner to be described hereinafter, gear 16 will be rotated in one direction and upon movement of clutch 20 to engage gear 14, gear 16, and hence drive member 17 and its associated roller will be rotated in a reverse direction.

Having reference now specifically to clutch 20 it will be seen that a groove 22 is provided in the center of clutch member 20 comprised of a pair of flanges 23 and 24. A pair of splines 25 extend upwardly above flange 23 and a similar pair of splines 26 extend downwardly from flange 24. Splines 25 are adapted to move upwardly under conditions to be described hereinafter into alignment with a pair of depending lugs 28 carried by gear 15. Similarly splines 26 are adapted to move downwardly into registry with corresponding upwardly extending lugs 28 carried by gear 14. A ratchet 29 is positioned around drive shaft 12 and provided with apertures 30 through which splines 25 pass. A suitable pin 27 may serve as the securing means for ratchet 29, passing through shaft 12 between upwardly extending splines 25. A similar ratchet 31 substantially identical in form to ratchet 29, provided with apertures corresponding to aperture 30 through which splines 26 may pass is also secured to drive shaft 12 in a similar manner as by a pin 21. Thus, ratchet 29 and 31 serve to hold clutch member 20 in non-rotatable relationship with drive shaft 12 but at the same time permit vertical movement thereof with respect to drive shaft 12. Additional purposes of ratchets 29 and 31 will be more fully pointed out hereinafter.

As best shown in Figure 2, a fork-like member 35 provided with inwardly turned extremities 36

is positioned adjacent groove 22 in such manner that extremities 36 interengage therewith, being held in position by flanges 23 and 24 whereby any movement imparted to member 35 is transmitted to clutch 20 and conversely, any movement of clutch 20 is transmitted through extremities 36 to fork-like member 35. Fork-like member 35 is pivoted as by pins 37 (see Figure 2) to a supporting bracket 38 which in turn is rigidly secured to suitable projections extending from the wall of casing 10, as by screws 39. Fork-like member 35 is provided with a vertically extending member 40 adjacent one of pivot pins 37 comprised of an upwardly extending portion 41 and a downwardly extending portion 42, which portions extend to points approximately adjacent ratchets 29 and 31 respectively.

Member 35 is also provided with a curved portion 43 adjacent the other of pivot pins 37. Curved portion 43 is provided, as shown in Figure 3, with an indented upper surface 44 adapted to be engaged by a ball 45 pressed into engagement therewith by a spring 46 contained in a housing 47. Housing 47 is rigidly secured to a cam surfaced member 48 carried by and rigidly secured as by a pin 49 to a control shaft 50. Control shaft 50 is provided at its upper extremity with an operating handle 51 extending exteriorly of casing 10.

Now from the foregoing, it will be seen that upon movement of operating handle 51 in a counterclockwise direction as seen in Figure 2, housing 47 and its associated ball 45 will be moved in a corresponding counterclockwise direction about curved member 43 to cause, by virtue of the indented portion 44 of member 43 previously discussed, an upward movement of the extremities 36 of fork-like member 35 as viewed in Figure 1. Such upward movement will be imparted to splines 25, which, it should be pointed out, extend, when the clutch mechanism is in the central or neutral position shown in Figure 1, only to the upper surface of ratchet 29, to cause the same to move upwardly into a position in which they will engage lugs 28 of gear 15 to cause rotation of the same and hence rotation of drive shaft 17 and its associated roller. Correspondingly upon movement of operating lever 51 in a clockwise direction, as viewed in Figure 2, ball 45 will ride up the other surface of indentation 44 and cause a downward movement of extremities 36 of fork 35 to cause engagement of splines 26 with lugs 28 of gear 14 to cause reverse movement of driving member 17 and consequently reverse rotation of its associated roller.

Means which will now be described are also provided whereby upon a movement of operating handle 51 to its central position from either of its two extreme positions, drive shaft 12 will of itself occasion return of the operating mechanism to such neutral position. A bracket, generally indicated at 55, is pivoted as by a pin 56 to suitable extending members which may comprise an integral part of the wall of casing 10. Bracket 55 is provided with two extending portions 57 and 58 each suitably recessed and provided with freely sliding blocks 59 and 60 within such recesses. Portions 57 and 58 extend to a position adjacent ratchet members 29 and 31 respectively, whereby block 59 serves under conditions to be described hereinafter as a pawl for ratchet 29 and block 60 as a pawl for ratchet 31.

Member 57 is provided with a curved portion 61 (see Figure 2) providing in effect a cam follower

for cam 48 which is provided with a recess 62 adapted to engage with cam follower 61. Thus when, by rotation of operating handle 51, operating rod 50 and hence cam 48 are rotated, portions 57 and 58 are moved about pivot 56 in a clockwise direction as viewed in Figure 2, permitting ratchets 29 and 31 to rotate freely with clutch 20 about driving shaft 12. However, upon a return of operating handle 51 to its central or neutral position, cam follower 61 re-engages its associated notch 62, whereupon blocks 59 and 60 fall into the path of rotation of ratchets 29 and 31 respectively. Upon the engagement of, illustratively, a tooth of ratchet 29 with block 59, block 59 is forced inwardly into abutting relationship with extending portion 41 of vertically extending member 40 and by the pressure exerted thereagainst causes a return of fork-like member 35 to its central position, thereby returning clutch 20 similarly to a neutral position.

Additional means are also provided for insuring the movement of bracket 55 completely out of path of movement of ratchets 29 and 31. Such means take the form of a spring 53 and an elongated aperture 54 (see Figure 2). Spring 53 serves, with the parts in the position shown in Figure 2, to bias bracket member 55 slightly in a clockwise direction about a fulcrum comprised of cam follower 61, elongated recess 54 permitting a slight movement of bracket 55 with respect to its normal pivot pin 56. Thus, it will be seen that when cam follower 61 is out of notch 62 and adjacent a high dwell of cam 48, the slight additional clearance provided by spring 53 and aperture 54 insures a complete clearance between blocks 59 and 60 and ratchets 29 and 31.

Assuming the operating handle to be in its opposite position whereby member 42 is closely adjacent block 60, a corresponding engagement of a tooth or ratchet 31 with block 60 will, by pressure exerted against extending portion 42, likewise return fork-like member 35 and hence clutch 20 to its central or neutral position.

Thus, it will be seen that by a mere finger tip pressure upon operating handle 51, clutch 20 is initially engaged and may be moved from neutral to either forward or reverse operating position, and correspondingly from either operating position to neutral since the actual movement of the clutch is done by power obtained from the drive shaft 12, operating handle 51 merely serving of itself to impart slight rotative movement to operating rod 50.

Means likewise are provided whereby the entire structure of the wringer may be rotated about the axis formed by drive shaft 12 during such time as the clutch mechanism above described is in neutral position but whereby such movement is precluded when the wringer rollers are rotated through clutch 20. Such means take the form, as shown in Figure 1, of a supporting bracket 64 coaxial with, and surrounding drive shaft 12 on which is mounted a collar 65 secured to bracket 64 in any desired manner as by a lug 66 engaging a suitable groove in bracket 64. Thus, it will be seen that upon rotation of housing 10, collar 65 remains stationary on bracket 64. Collar 65 is provided with a plurality of apertures 67 provided with substantially conical bottom portions 68. Adjacent collar 65 is a downwardly extending bore 69 in substantial alignment with operating rod 50. Bore 69 is provided with an aperture 70 which when the wringer is moved follows a path in registry with apertures 67, into which projects a spherical member 71 of a diameter adapted to fit

snugly within one of recesses 67. Adjacent ball 71 is a member 72 provided with a cam surface 73 and a shoulder 74 against which one end of a spring 75 abuts. The other end of spring 75 abuts a shoulder 76 at the upper extremity of bore 69. A rod 77 of a diameter substantially equal to that of operating rod 51 extends upwardly from member 72 and passing through a suitable aperture 79 terminates adjacent the lower portion of operating rod 50. The upper end of rod 77 is provided with a stepped surface comprising a lower portion 78 and an upper portion 80. Correspondingly the lower end of operating rod 50 is provided with a stepped surface comprising a lower portion 81 and an upper portion 82. With the parts in position shown it will be seen that portion 78 is adjacent portion 81 and portion 80 adjacent portion 82 in such manner as to permit a clearance between the effective adjacent ends of operating rod 50 and rod 77. Thus upon rotation of the wringer and hence housing 10 about shaft 12 upon removal of aperture 70 from juxtaposition to a recess 67, sphere 71 is forced outwardly with respect to aperture 67 due to the conical bottom surface 68 of the recess 67 and through engagement with cam surface 73 and the bottom of bore 69, forces member 72 and hence rod 77 upwardly against the pressure of spring 75 until such time as aperture 70 is adjacent a second recess 67 whereupon the ball 71 may resume its position as shown.

It will, therefore, be readily understood that any desired number of recesses 67 may be formed in collar 65 to provide any desirable plurality of positions through which the wringer may be moved. It will be further understood that the pressure of spring 75 is sufficiently great to resist free rotating movement of the wringer about shaft 12 in the absence of a substantial pressure exerted thereon.

It will additionally be seen, however, that when operating handle 51 is moved to impart motion to the rollers in the manner previously discussed, low surface 81 of operating rod 50 is juxtaposed to high surface 89 of rod 77 in such manner as to remove the clearance between the adjacent ends of these rods. When the parts are in such position, therefore, rod 77 is held securely against movement and likewise sphere 71 forms, in effect, a pin and aperture connection through its associ-

ation with recess 67 and hence precludes the possibility of rotation of the wringer during such time as the rollers are in operation.

Thus, from the foregoing it will be seen that the structure herein before described and shown in the accompanying drawings accomplishes all the objects of this invention including many advantages of great practical importance. As many embodiments may be made of the invention, and as many modifications may be made in the embodiment herein shown and described, it is to be understood that all matter hereinbefore set out and/or shown in the drawings, is to be interpreted merely as illustrative and to be limited only by the scope of the appended claims.

I claim as my invention:

1. In a device of the character described, in combination a driving member, a driven member, a clutch member therebetween, an operating shaft, a forked member pivoted adjacent said operating shaft, a cam surface on said forked member, a cam follower carried by said operating shaft whereby movement of said operating shaft is imparted to said forked member and movement of said forked member is imparted to said clutch and means carried by said driving member to move said forked member and hence said clutch upon a change in position of said cam follower carried by said operating shaft.
2. In a device of the character described, in combination a driving member, a driven member, a clutch member therebetween, an operating shaft, a forked member pivoted adjacent said operating shaft, a cam surface on said forked member, a cam follower carried by said operating shaft whereby movement of said operating shaft is imparted to said forked member and movement of said forked member is imparted to said clutch and means carried by said driving member to move said forked member and hence said clutch upon a change in position of said cam follower carried by said operating shaft, said means including a ratchet carried by said driving member and a pawl associated with said forked member and means whereby movement of said operating shaft juxtaposes said pawl to said ratchet to cause movement of said forked member therethrough.

THOMAS W. BEHAN.

CERTIFICATE OF CORRECTION.

Patent No. 2,297,997.

October 6, 1942.

THOMAS W. BEHAN.

It is hereby certified that error appears in the above numbered patent requiring correction as follows: In the heading to the drawings, Sheets 1 and 2, name of inventor, for "T. E. BEHAN" read --T. W. BEHAN--; and that the said Letters Patent should be read with this correction therein that the same may conform to the record of the case in the Patent Office.

Signed and sealed this 12th day of January, A. D. 1943.

Henry Van Arsdale,
Acting Commissioner of Patents.
